Rudolph J. Dorn
ATTORNEY

UNITED STATES PATENT OFFICE.

CHARLES P. DORN, OF NAPERVILLE, ILLINOIS.

DOOR-CHECK.

No. 914,340.

Specification of Letters Patent.

Patented March 2, 1909.

Application filed July 24, 1908. Serial No. 445,151.

To all whom it may concern:

Be it known that I, CHARLES P. DORN, citizen of the United States, residing at Naperville, in the county of DuPage and 5 State of Illinois, have invented certain new and useful Improvements in Door-Checks; and I do hereby declare the following to be a full, clear, and exact description of the invention, such as will enable others skilled in 10 the art to which it appertains to make and use the same.

This invention relates to a novel construction in a door check, the object being to provide a simple and efficient device of this 15 character by means of which the door may be secured at any desired point in its movement, and consists in the features of construction and combinations of parts hereinafter fully described and claimed.

20 In the accompanying drawings illustrating this invention: Figure—1—is a plan section of a door equipped with a check constructed in accordance with my invention. Fig.—2—is a plan section of the door check. Fig.—3—is 25 a front elevation of the clamping member of the check. Fig.—4—is a longitudinal section of the spring employed. Figs.—5—and —6—are respectively a plan section and a vertical section of the clamping member.

30 My said device comprises a pivot member adapted to be secured to the door frame adjacent the hinged end of the door, a flat spring pivotally secured to said member, and a clamping member secured to the door and 35 adapted to engage said flat spring to lock the door against movement in either direction.

The particular object of the invention is to provide a door check which is simple and efficient in its construction and positive in its 40 operation.

The device comprises the plate A provided with parallel projections B between which the looped end of the flat spring C is received. A pin D passes through said projections and 45 said loop of said spring to pivotally secure the latter. The said plate A is secured to the door frame E adjacent the hinged end of the door F and to the latter is secured the clamping member through which the free end portion of the spring C passes. Said clamping 50 device comprises a substantially U-shaped

plate G provided at the free ends of its arms with flanges H having openings therein for the passage of screws, the said free ends of the arms of said member being connected with 55 each other by means of cross-bars I disposed on either side of the middle portion of said plate. A thumb-screw J enters a central threaded opening in said plate G and is adapted to bear upon the spring C midway 60 between the bearing points of the bars I thereon, thus exerting a distorting pressure on said spring whereby the latter is prevented from moving longitudinally relatively to said clamping member. The said spring 65 C consists preferably of a folded strip of spring steel, one leaf thereof being slightly longer than the other and having its free end portion K folded over upon the free end of the shorter leaf to secure the latter. The 70 double spring thus formed is advantageous in that it is more resilient than a single spring of the same thickness and can be more readily firmly clamped without danger of breaking. At the same time it is sufficiently 75 stiff to resist great compression strains without buckling.

I claim as my invention:

A door check comprising a member secured to the door casing, a flat spring pivotally 80 secured to said member at one end, a clamping member secured to the door and comprising a U-shaped plate provided at the free ends of its arms with flanges having openings 85 therein, screws passing through the said openings, cross-bars connecting said arms on either side of the middle of the said plate, a thumb-screw mounted in a central threaded opening in said plate, said flat spring passing at its free end portion between the web portion 90 of said plate and said cross-bars and adapted to be engaged by said thumb-screw midway between the bearing points of said bars thereon whereby a distorting pressure 95 is exerted on said spring.

In testimony whereof I have signed my name in presence of two subscribing witnesses.

CHARLES P. DORN.
